POWER WASHER

Orlan M. Arnold, Grosse Pointe Park, Mich., assignor to Ajem Laboratories, Inc., Livonia, Mich.

Application March 26, 1956, Serial No. 573,883

8 Claims. (Cl. 134—64)

The present invention relates to metal processing apparatus for treating the surfaces of a workpiece with jets of a treating fluid and more particularly to improvements in apparatus of the type described and claimed in an application for United States Letters Patent of Willard L. Johnson, Serial No. 571,415, filed March 14, 1956, and assigned to the same assignee.

Such apparatus may be used for pickling, anodizing, or otherwise chemically treating a surface or surfaces of a workpiece, but is particularly adapted for use as a power washer for removing dirt or industrial waste and residue from such surfaces between processing operations. For example, the apparatus is adapted to clean the polished surfaces of a flexible or rigid sheet, strip, or other shape in continuous webs or segmented lengths that have a generally linear form. The cleaning is accomplished by the erosive scouring action of liquid jets issuing from liquid-distributing members arranged at opposite sides of and closely adjacent to the surfaces to be cleaned.

One of the objects of the present invention is to provide an improved apparatus of the type indicated for simultaneously impinging the surfaces of a workpiece with jets of different fluids.

Another object is to provide an apparatus of the type indicated for impinging the surfaces of the workpiece with jets of a gas as well as a liquid to produce a multiphase of liquid and gas bubbles which enhances the action of the liquid in cleaning the surfaces, particularly with certain kinds of soil.

Another object is to provide an apparatus in which the jets of fluid are particularly effective in supporting the workpiece during a cleaning or other processing operation.

Still another object is to provide an improved apparatus which is of simple and compact construction to adapt it for economical manufacture and which may be easily serviced for cleaning or repair, or for the substitution of orifice patterns.

In this specification and accompanying drawings I have shown and described a preferred embodiment of my invention and suggested various modifications thereof; but it is to be understood that these are not intended to be exhaustive nor limiting of the invention, but on the contrary are given for purposes of illustration in order that others skilled in the art may fully understand the invention and the principles thereof and the manner of applying it in practical use so that they may modify and adapt it in various forms, each as may be best suited to the conditions of a particular use.

In the drawings:

Fig. 1 is a sectional view of a power washer incorporating the novel features of the present invention;

Fig. 2 is a sectional plan view taken on line 2—2 of Fig. 1, to show the pattern of orifices in the orifice plate of one of the liquid-distributing members;

Fig. 3 is an enlarged sectional view of a portion of a

2

liquid-distributing member to show the detachable connection between the air tubes, partition wall and the orifice plate;

Fig. 4 is an enlarged sectional view of a liquid-distributing member of modified construction;

Fig. 5 is an enlarged view of a still further modified construction for producing a jet of combined liquid and gas, and

Fig. 6 is a sectional view of a portion of a liquid-distributing member showing an orifice for producing an inclined jet.

Fig. 1 illustrates an apparatus of general application for treating a workpiece W with jets of a treating fluid, but for purposes of description the apparatus will be described as a power washer for cleaning the surfaces thereof. The apparatus comprises a tank 6 having a bottom wall 7 and end walls 8 and 9 in the direction of movement of the workpiece W. The back wall 10 and a front wall (not shown) extend upwardly beyond the end walls and mount beams 11. A hood 12 extends between and along the beams 11 and has depending end portions 13 and 14 which together with the front and back walls enclose the working parts of the washer. The depending end portions 13 and 14 of the hood 12 extend below the liquid level in the tank 6 to prevent the escape of treating liquid from the apparatus, and the end portions have openings 15 and 16 to permit movement of the workpiece W therethrough.

The workpiece W is fed through the apparatus by sets 30 of feed rolls 19 and 20 adjacent each end thereof and the feed rolls are supported by brackets 21 depending from the beams 11. Juxtaposed liquid-distributing elements 22 and 23 are located between the sets of feed rolls 19 and 20 at opposite sides of the workpiece W.

Each of the liquid-distributing members 22 and 23 has a flat plate 24 located closely adjacent the workpiece W with orifices 25 therein arranged in a pattern to issue jets of the cleaning liquid for impinging all areas of the surfaces of the workpiece W. The liquid-distributing members 22 and 23 also are supported by brackets 26 depending from the beams 11. Liquid-distributing members 22 and 23 together with the opposed drive rolls of each set 19 and 20 are mounted on their supporting brackets 21 and 26, respectively, for adjustment toward and away from each other to adapt them for a workpiece W of any size or shape. As thus far described, the apparatus is like that described and claimed in the application for U.S. Letters Patent of Willard L. Johnson, referred to above.

In accordance with the present invention, the fluid-distributing members 22 and 23 are constructed to impinge the surfaces of the workpiece W with jets of fluid including a gas as well as a liquid. The liquid and gas may be delivered from the liquid-distributing members 55 22 and 23 in separate jets or as jets of combined liquid and gas. The liquid and gas may comprise treating chemicals, but when the apparatus is used as a power washer, the liquid comprises a washing liquid such as water with or without a soap, detergent and corrosion inhibitor and the gas is air. The jets of liquid and gas produce a multiphase of liquid and gas bubbles on the surface of the workpiece which has been found to be particularly effective in removing certain kinds of soil. Furthermore, the jets of gas are especially effective in

60 supporting a flexible workpiece W during its passage between the liquid-distributing members 22 and 23 by providing an additional cushion on which the workpiece rides.

In the embodiment of the invention illustrated in Figs. 70 1-3, each fluid-distributing member 22 or 23 is constructed to deliver the liquid and gas in separate jets and the separate jets are arranged to produce an effective

multiphase action of gas and liquid bubbles over the entire surface of the workpiece. It is to be understood, however, that a multiple fluid-distributing member may be used on one side of the workpiece only, preferably at the bottom, with a single fluid-distributing member on the top. Each multiple fluid-distributing member 22 or 23 is in the form of a box and, as illustrated, comprises a marginal frame 28 in the form of a finished casting having bosses 29. The side of the liquid-distributing member 22 or 23 adjacent the workpiece W is closed by the orifice plate 24 and the side remote from the workpiece W is closed by a cover plate 30. A partition wall 31 is provided in each liquid-distributing member 22 or 23 which divides it into an outer air chamber 32 and an inner liquid chamber 33. The division wall 31 may be formed as an integral part of the marginal frame 30 with a portion 35 parallel with the orifice plate 24 and a portion 36 extending at right angles thereto. Partition wall 31 has a liquid inlet opening 37 therein with a nipple 38 extending outwardly through cover plate 30 and a plurality of smaller openings 39 with tubes 40 depending therefrom, see Fig. 3. The upper ends of the tubes 40 project into the openings 39 and are attached to the partition wall 31 as by welding, brazing or the like.

The orifices 25 in the illustrated embodiments are formed by holes drilled through the orifice plate at right angle to its surfaces. In some applications it may be desirable to drill the orifice holes 25 at an acute angle to the surface of the orifice plate 24 to produce angular jets for tangential impingement of the workpiece W and in other applications it may be desirable to provide a nozzle for producing a particular character of jet and such nozzle is preferably located at the interior of the liquid-distributing member, all of which are described and claimed in the copending application of Willard L. Johnson, Serial No. 571,415, referred to above. Certain of the orifices 25b are countersunk on the inner side of the plate 24 to receive the ends of the tubes 40 depending from the partition wall 31 and a recess 42 is provided in the plate to receive the lower edge of the vertical portion 36 of the dividing wall 31. Preferably, gaskets 43 and 44 are provided between the ends of the tubes 40 and edge of the wall portion 36 to seal the joints and provide detachable connections therebetween. The orifice plate 24 and cover plate 30 are detachably connected to the open sides of marginal frame 28 by means of machine screws 45 or the like which are screwed into the tapped bosses 29 on the frame 28. The cover plate 30 has an opening 48 for the nipple 38 and the joint therebetween is sealed by a ring 49 and packing 50, see Fig. 4. Nipple 38, in turn, is connected through a pipe 51 to a source of cleaning liquid which is supplied to the inner liquid chamber 33 under pressure. The cover plate 30 has a second opening 52 connected by a pipe 53 to a source of air which is supplied under pressure to the other air chamber 32.

Orifices 25 are arranged in a pattern in the orifice plate 24 to impinge all surfaces of the workpiece W with both cleaning liquid and air. As illustrated in Fig. 2, the orifices 25 are arranged in five rows in the portion of the orifice plate 24 underlying the chamber 33 and two rows underlying the chamber 32 at the left of the portion 36 of the partition wall 34. Each row of orifices 25 is spaced from the other rows in the direction of movement of the workpiece W and extends throughout the entire width thereof. The cleaning liquid at high pressure in chamber 33 issues from certain of the orifices 25a in high velocity jets which impinge the surfaces of the workpiece with considerable impact to loosen and remove dirt, industrial waste and other residue by an erosive scouring action. Removed dirt is washed away with the cleaning liquid which flows into the tank 6 at the sides of the workpiece W and liquid-distributing members 22 and 23. Dirt is separated from liquid in the tank 6 and the cleaning liquid is recirculated to continue the cleaning operation.

Orifices 25b connected by tubes 40 to the air chamber 32 issue jets of air against the surface of the workpiece W at high velocity. As will be observed by reference to Fig. 2, the orifices 25b connected to air chamber 32 are arranged in a pattern adjacent a plurality of orifices 25a from which the cleaning liquid issues. The air mixes with the cleaning liquid over the entire surface of the workpiece W to produce a multiphase of liquid and gas bubbles which augments the erosive cleaning action of the jets of liquid, especially with certain kinds of soil.

The two rows of orifices 25c beyond the partition wall 36 underlie the air chamber 32 and issue a curtain of high-velocity jets of air against the surface of the workpiece W. The curtain of air sweeps the cleaning liquid and removed dirt suspended therein rearwardly in the direction of movement of the workpiece W to further scour and dry the surfaces prior to engagement by the drive rolls 19. In other words, the air curtain insures the removal of all scale to prevent it from entering the bight of the drive rolls of the set 19 which might score the drive rolls or surface of the workpiece W.

The jets of liquid and gas impinge the opposite sides of the workpiece W with considerable force and the pattern and size of the orifices 25a, 25b and 25c in the opposite liquid-distributing members 22 and 23 are so arranged as to balance the total forces and support the workpiece during its passage between the members. The liquid and air issuing from the orifices 25a, 25b and 25c provides a cushion of combined liquid and air especially at the underside of the workpiece W, on which the workpiece rides during its movement between the members 22 and 23. The cushion of air and liquid is especially effective in supporting the workpiece with less frictional drag than when liquid only is used.

Fig. 4 illustrates a liquid-distributing member 22 or 23 of modified construction in which a partition or division wall 60 extends across the entire area of the member to divide it into an inner liquid chamber 61 adjacent the workpiece W and an outer air chamber 62 overlying the inner chamber. The liquid-distributing member is formed by adjacent marginal frames 63 and 64 with the division wall 60 in the form of a plate located therebetween and closed on one side by an orifice plate 65 and on the other side by a cover plate 66. The parts are held in assembled relation by means of bolts 67 extending through the orifice plate 65, bosses 69 in marginal frame 64, intermediate division wall or plate 60, bosses 68 on marginal frame 63, and cover plate 66. The partition wall 60 has depending tubes 70 sealed thereto which align with countersunk recesses 71 surrounding certain of the orifices 72 in the orifice plate, as explained with respect to Fig. 3 of the drawing, to permit the orifice plate 65 to be detached for cleaning, repair, or substitution of an orifice pattern. The pattern of orifices 72a and 72b communicating with chambers 61 and 62, respectively, for cleaning liquid and air, may be the same as the pattern orifices 25a and 25b explained with reference to the embodiment of the invention illustrated in Figs. 1-3. The two rows of orifices 71c for producing a curtain of air are connected to the air chamber 62 by tubes 70. Liquid is supplied at high pressure to the inner chamber 61 through the pipe 51 and nipple 38 connections of the same construction as described with respect to Fig. 1, and air is supplied to the other chamber 62 by a pipe connection 53.

In some applications it may be desirable to issue jets of combined liquid and gas to further break up the liquid into high velocity drops and thereby increase the impact and erosive scouring action of the jets. Such a modified arrangement is illustrated in Fig. 5 of the drawing in which tubes 80 project from the air chamber 81 toward the orifice plate 82 and have tapered ends 83 projecting into correspondingly shaped orifices 84 in spaced relation thereto. The annular space 85 between the tapered end 83 of the tube 80 and orifice 84 permits an annular ring of the high pressure liquid to issue from the orifice simul-

taneously with a jet of high pressure air from the end of the tube 80. The jet of high pressure air tends to break up the converging cone of liquid into high velocity drops for impinging the surface of the workpiece W with a high impact force. In some applications it may be desirable to supply both air and liquid at high pressure to a single chamber where the air and water mix in a homogeneous mass which issues from the orifices to produce the same results.

It will now be observed that the present invention provides fluid-distributing members of improved construction for impinging the surface or surfaces of the workpiece with jets of different fluids. It will further be observed that the present invention provides a fluid-distributing member for impinging the surface or surfaces of a workpiece with jets of a gas as well as a liquid, to produce a multiphase action of liquid and gas bubbles which enhances the cleaning operation with certain types of soil. It will further be observed that the present invention provides a fluid-distributing member which is particularly effective in supporting the workpiece during its passage between members. It will still further be observed that the present invention provides an improved fluid-distributing member which is of simple and compact structure adapted for economical manufacture and one which is easily and quickly dismantled for cleaning, repair or substitution of orifice patterns.

While several embodiments of the invention are herein illustrated and described, it will be understood that further modifications may be made in the construction and arrangement of elements without departing from the spirit or scope of the invention. Therefore, without limitation in this respect, the invention is defined by the following claims.

I claim:

1. Apparatus for treating surfaces of a workpiece by subjecting it to the multiphase scouring action of jets of liquid and gas comprising rectangular fluid-distributing boxes arranged at opposite sides of the workpiece and extending throughout the width and for a substantial distance along the workpiece, at least one of the fluid-distributing boxes having a continuous rectangular orifice plate overlying one side thereof and adjacent the workpiece, an outer closure plate and an intermediate partition cooperating with the orifice plate and closure plate to form separate chambers, the orifice plate being detachably mounted on the box and having a contour corresponding to the shape of the workpiece with a pattern of jet forming orifices therein, one of the chambers formed by the intermediate partition walls overlying at least a part of the orifice plate and the other chamber overlying the first chamber, tubes extending from the intermediate partition wall in communication with the outer chamber and overlying certain of the orifices in the orifice plate, means for supplying liquid and gas, respectively, to the separate chambers of the fluid-distributing member at high pressure which issue from the orifices in the form of jets of liquid and gas, and means providing unrestricted flow of liquid from the workpiece to cause the jets to directly impinge on the surfaces of the workpiece at high velocity to produce the multiphase scouring action of liquid and gas.

2. Apparatus in accordance with claim 1 in which at least a portion of the partition wall extends at right angles to the orifice plate to divide the box into liquid and air chambers in the direction of movement of the workpiece, and means for detachably connecting the orifice plate to the box and partition wall.

3. Apparatus in accordance with claim 1 in which at least a portion of the partition wall is parallel to the

orifice plate to divide the box into a liquid chamber adjacent the orifice plate and an air chamber remote from the orifice plate, and the tubes extending from the remote chamber through the adjacent chamber to overlie at least some of the orifices in the orifice plate.

4. Apparatus in accordance with claim 3 in which the tubes are connected in sealing engagement with the partition wall and orifice plate to issue air and cleaning liquid in separate jets.

5. Apparatus in accordance with claim 3 in which the tubes project from the air chamber and have end portions projecting into at least certain of the orifices in spaced relation thereto to produce jets of combined liquid and air.

6. Apparatus in accordance with claim 1 in which the liquid-distributing box has a partition wall providing a chamber overlying a portion of the orifice plate and a second chamber overlying the first chamber and another portion of the orifice plate, tubes extending from the overlying chamber through the adjacent chamber in sealing engagement with at least some of the orifices in the orifice plate, and means for feeding a cleaning liquid to the adjacent chamber overlying the orifice plate and air to the chamber overlying the adjacent chamber.

7. Apparatus in accordance with claim 1 in which the liquid-distributing member is formed by an inner orifice plate, an outer cover plate and an intermediate partition plate with marginal frames therebetween, means for supplying a liquid under pressure to the chamber formed between the orifice plate and intermediate plate, means for supplying air under pressure to the chamber formed between the intermediate plate and cover plate, and tubes extending between the intermediate plate and orifice plate in the last row of orifices in the orifice plate in the direction of movement of the workpiece.

8. Apparatus for simultaneously treating a surface of a workpiece with a cleaning liquid and air comprising fluid-distributing members in the form of boxes arranged at opposite sides of the workpiece and closely adjacent thereto, means for feeding the workpiece between the fluid-distributing members, the plates of the fluid-distributing members adjacent the workpiece having a contour corresponding to the shape of the workpiece and a pattern of jet forming orifices therein, at least one of said fluid-distributing boxes having a partition wall to divide it into separate chambers, one of the chambers overlying at least a part of the orifice plate and the second chamber overlying the first chamber, certain of the orifices communicating directly with the chamber directly adjacent thereto, tubes in sealing engagement with the partition wall and orifice plate around the other orifices therein, means for feeding a cleaning liquid to one of said chambers and air to the other chamber at high pressure which issues from the orifices in separate jets, and means providing unrestricted flow of liquid from the workpiece to cause the jets to directly impinge on the surface of the workpiece at high velocity to produce a multiphase action of liquid and gas bubbles thereon.
